CLAIM

The ornamental design for a legwear as shown and described.

DESCRIPTION

FIG. 1 is a right side view of a legwear showing our new design;

FIG. 2 is a left side view thereof;

FIG. 3 is a front view thereof;

FIG. 4 is a rear view thereof;

FIG. 5 is a top view thereof;

FIG. 6 is a bottom view thereof; and,

FIG. 7 is a perspective view thereof.

In the drawings, the dashed broken lines depict portions of the legwear that form no part of the claimed design. The dot-dash broken lines define the boundaries of the claimed design, and form no part of the claimed design.

1 Claim, 3 Drawing Sheets
